UNITED STATES PATENT OFFICE.

EDWARD N. TRUMP AND FRANK FRIEDRICH, OF SYRACUSE, NEW YORK, ASSIGNEES
TO HUMPHREY GAS PUMP COMPANY, A CORPORATION OF NEW YORK.

PUMP.

1,349,395.

Specification of Letters Patent. Patented Aug. 10, 1920.

Application filed August 31, 1918. Serial No. 252,152.

To all whom it may concern:

Be it known that we, EDWARD N. TRUMP, a citizen of the United States, residing in Syracuse, county of Onondaga, State of New York, and FRANK FRIEDRICH, a subject of the King of Great Britain, residing in Syracuse, county of Onondaga, State of New York, have invented a new and useful Improvement in Pumps, of which the following is a specification.

The invention relates to pumps. The object is to provide an improved pump driven by any suitable power medium. The invention comprises means for reciprocating a pipe or tube having a suitable valve, in which the weight, inertia and momentum of the pipe and its contents are utilized in connection with the functions of the actuating means or power medium.

20 This application is a continuation in part of application Serial No. 95,062 filed May 3, 1916.

The kinetic energy of the moving parts is utilized to do useful work in such a way as 25 to secure the operation of a steam cylinder more economically than heretofore possible in a direct acting steam pump. Better economy may also be secured in a similar way in connection with an internal combustion cylinder or other power generating means.

In the prior art it has been proposed to reciprocate a pipe or tube with a foot valve to cause water to be delivered therethrough, but in none of these prior devices is any 35 suggestion found of utilizing the kinetic energy to secure an economical operation of a power generating means.

The direct acting well pump now in common use, comprises a steam cylinder directly 40 connected to a pump which is located in a well. These pumps are efficient as regards mechanical losses, but are inefficient as regards steam consumption, because, in common with other types of direct acting steam pumps, they cannot use the steam expansively, and the steam consumption of these pumps is very large.

In respect to reciprocating tube pumps it 45 has been found that, besides the normal energy required for simply raising the water, a nearly equal additional energy is required to give the tube the necessary acceleration to secure an efficient operation of this type of pump. This represents kinetic energy stored 55 in the tube, and, if not utilized involves loss

of energy as compared with present direct acting steam pumps.

The first step in this invention therefore is to provide means for utilizing or recovering this kinetic energy, so far as possible and, 60 although all this energy cannot be fully utilized the extreme simplicity and low first and maintenance cost of the tube pump is such as to offset this small loss and bring the tube pump into general use.

65 The second step of the invention in its most complete form consists in recovering and utilizing this kinetic energy in such a way as to permit of using steam or other motor fluid expansively and, by operating on the 70 Stumpf cycle, we reduce the steam consumption so that we are able to produce a direct acting well pump which not only gives a steam consumption very much less than that of the present direct acting steam pumps but 75 the pump part of the device costs less to construct, less to install and less to maintain.

The means to recover the kinetic energy, 80 mentioned as the first step, may be a cylinder containing an elastic medium with a piston operating therein connected to the piston rod, in which the piston will compress the elastic medium in the cylinder by the kinetic energy, and the compressed cushion will react to help acceleration in the return stroke.

85 In the second step the means used in a steam pump are the combination of this compression of an elastic cushion, with the short cut-off of the steam. That is, we admit the steam at the beginning of the upstroke. We 90 cut it off, using the steam expansively, and thereby utilize all of the kinetic energy in the water and perhaps part of the kinetic energy in the tube to complete the stroke. When the piston reaches the upper part of 95 the cylinder, and the exhaust ports open to exhaust the steam, the piston moves into the upper end of the cylinder which forms an air cushion and the remaining kinetic energy in the tube is stored in this air cushion which 100 reacts and causes the tube to descend at a velocity greater than the velocity due to gravity, which is desirable in this form of pumping. As soon as the piston emerges from the air cushion the exhaust ports are 105 closed, thereby trapping the steam in the lower part of the cylinder which is compressed by the kinetic energy in the tube to a point approaching initial steam pressure, which compression stops the downward mo- 110

tion of the tube and gives the high compression necessary to the Stumpf cycle.

This method of utilizing the kinetic energy, so that it permits of a great expansion on the upstroke and of high compression on the downstroke enables this form of pump to be operated by an internal combustion cylinder with or without the use of crank or flywheel. Where a flywheel or crank is used, the cushion cylinder not only is desirable to absorb kinetic energy but also to prevent the shock on the bearings which would otherwise result from the acceleration and retardations above referred to. The only difference between steam and internal combustion is that it is the combustion of the gas or oil that gives the initial impulse on the upstroke, which also must be used expansively, and there is gas or air instead of steam in the cylinder which forms the compression on the downstroke, which compression is also essential to the operation of an internal combustion engine.

Referring to the drawings, which illustrate merely by way of example suitable means for effecting our invention;

Figure 1 is a vertical section of a pump embodying the invention, in which the power cylinder is a single acting una-flow steam cylinder.

Fig. 2 is a similar view showing a separate cushioning cylinder especially useful with condensing steam engines.

Fig. 3 is a similar view showing crank and flywheel means for actuating the tube, using the cushioning cylinder as in Fig. 2.

Fig. 4 is a similar view showing a single acting una-flow steam power cylinder and piston with a differential piston connected therewith operating in a cushioning cylinder.

Fig. 5 is a vertical section showing a power cylinder adapted to use liquid fuel.

Similar numerals refer to similar parts throughout the several views.

Referring to Fig. 1, the power piston 11 operating in the una-flow single acting steam cylinder 12 is connected by the piston rod 13 through the yoke 14 with the tube 15 having the foot-valve 16. Cylinder 12 is provided with the jacketed head 17 and the steam admission valve 18. The steam is led to the jacketed head 17 through the supply pipe 19 and passes from the jacketed head 17 through the valve 18 into the cylinder 12 below the piston 11. The steam pressure beneath the piston 11 carries it upwardly with the tube 15, and, after cut-off, the continued expansion of the steam and the kinetic energy acquired by the tube causes a continued upward movement of the piston until it passes and opens the exhaust ports 20 so that the expanded steam will pass therethrough to the exhaust belt 21 and thence to exhaust pipe 22. After passing

the ports 20' the piston 11 traps and compresses an elastic cushion in the top of cylinder 12 which brings the piston and tube to rest and then re-acts to accelerate the downward movement thereof. After covering 70 the exhaust ports 20, in its downward movement, the piston traps the steam which has not escaped and compresses the same back against the heated head as required for securing an effective Stumpf cycle. This 75 downward stroke which is caused primarily by the reaction of the compressed cushion at the top of the cylinder, co-operating with the force of gravity, results in a far more effective compression of the steam in the 80 cylinder head than would be due to gravity alone. The compressed steam in the cylinder head also serves as a cushion finally to arrest the downward movement of the piston and the tube.

Upon the upstroke of the piston and tube the water that has entered the bottom of the tube past the foot-valve, to the level of the supply in the well, is also carried upwardly and when the piston comes to rest due to 90 the compression of the elastic cushion at the top of the cylinder, the water in the tube cannot stop so suddenly and consequently flows by momentum upwardly, drawing in more water through the foot-valve 16.

The compressed elastic cushion in the top of the cylinder 12, as above stated, will start the piston and tube downwardly at a velocity greater than that due to gravity so that water will continue to rise in tube 15, and consequently more water will enter past foot-valve 16.

It can readily be seen that the degree of said compression by the downstroke will depend upon the relative velocities of the water and the tube, and it may be possible to operate the tube at so high a velocity that the water would not come to rest at all, but that the tube would start on its second upward stroke before the water had entirely come to rest on its first upward movement. This it can readily be understood gives a wide range of conditions in order to obtain any desired compression.

With respect to the admission of steam to 115 cylinder 12, means are provided for controlling the actuation of valve 18 so as to permit of a considerable movement of the piston after passing the point necessary to secure the operation of the valve actuating mechanism.

This may be called a delayed or retarded valve actuation. It consists in moving the valve spindle 23 by the operation of the lever 24 connected by link 25 with yoke 14, 125 so that the spindle is brought to such a position before piston 11 has reached the end of its downstroke, to open communication between the space to the rear of valve piston 26 and the exhaust so that the pressure 130

is relieved to permit the opening of valve 18, due to the pressure on the opposite side of said valve piston 26. The time required to relieve this pressure, after the actuation 5 of the valve spindle 23, is regulated by a needle valve 27, so that any required delay may be secured.

Cut-off is secured by moving the spindle into the position establishing communication 10 between the steam pressure and the space to the rear of valve piston 26 to cause the closing of valve 18.

One very great advantage of the steam tube pump without discharge valve is that 15 it is possible to vary the capacity by simply varying the cut-off; whereas in any other form of steam pump using steam expansively, when the capacity is small, the cut-offs have to be lengthened to prevent stopping 20 on the dead center.

In Fig. 2 the means for reciprocating the tube 15 comprises the single acting una-flow steam cylinder 28 having the piston 29 connected with the piston rod 30. An additional piston 31 is provided on the rod 30, which piston operates in the cylinder 32 which is provided with openings 33 intermediate its two ends, but which is closed at its lower end forming an air cushion or 25 check for the down stroke of said rod 30. Such a device may be desirable when running condensing, and there should not be sufficient cushion in the trapped steam properly to check the weight of the parts. There 30 may be conditions in which it is desirable to have both ends of this air cylinder closed to form an air cushion or check for each 35 end of the reciprocating movement.

In Fig. 3 the means for reciprocating the 40 tube comprises the crank 19 and flywheel 19' driven by any suitable primary medium. In this case the cushioning cylinder 32 and piston 31 are also used to absorb and give out energy and prevent shock to the bearings 45 due to the acceleration and retardation of the tube. In this example the cylinder 32 is shown closed at each end and provided with openings 33 intermediate its two ends.

In Fig. 4 a differential piston 34, 35, is 50 provided having the extension 35 of greater diameter; 34 being the power piston operating in the power cylinder 36 while 35 operates in the air cushion cylinder 37.

Referring to Fig. 5, which shows an 55 internal combustion power cylinder 38; the compressed charge which is expanded below the piston 39 forces the piston upwardly carrying with it the tube 15. Air is compressed in the cylinder 38 above the piston 60 and also in the annular space 40, which is in communication with the cylinder through ports 41. When the piston 39 covers the ports 41, an air cushion is compressed at the top of the cylinder until the upward 65 movement of the piston is arrested. When

the piston passes above and uncovers the ports 41, and at the same time the tappet 42 on piston rod 43 encounters the stem 44 of valve 45, which opens this valve, the compressed air in annular space 40 rushes 70 through ports 41 into cylinder 38 to drive out the burnt products through port 46. A fresh supply of air enters space 40 past non-return valve 40'. It may in some cases, be desirable to use a differential piston and 75 cylinder similar to that shown in Fig. 4, to increase the volume of scavenging air.

During the upstroke of piston 39 the spring 47 will actuate, through lever 48, the rod 49 of the plunger operating in the cylinder 50 to draw in a charge of liquid fuel from a suitable source of supply through pipe 51. Upon the downstroke of the piston 39, the projection 52 connected with the piston rod 43 will engage the tappet 53 on 80 rod 54 to move the lever 48 and plunger rod 49 in the opposite direction, to force a charge of liquid fuel through pipe 55 into cylinder 38 through a suitable spraying nozzle not shown. It will be understood that 85 this liquid fuel is sprayed into the cylinder into air compressed by the downstroke of the piston and thus we have a compressed charge for the next stroke.

Where a gas cylinder is used with an exhaust valve and that valve should leak badly or should become stuck open, or where for any reason there might not be sufficient compression in the cylinder properly to arrest the working parts at the end of the downstroke, it will be desirable to provide some form of dash-pot for cushioning the parts and preventing too great a shock. It is of course desirable that this dash-pot should not be acting until the descending piston is 100 105 near the bottom of the cylinder or at the point of designed compression, in order that the dash-pot will not interfere with the compression.

In Fig. 5 is shown a simple form of hydraulic dash-pot in which the holes 56 in the pipe 57 let the water flow freely in and out of the annular space 58, but when the holes are covered by the enlargement 59 of tube 15, the water remaining in the annular 110 115 space 58 being forced out through small orifices or by the leakage between the tube and the surrounding pipe, makes an effective hydraulic dash-pot.

The means illustrated in the drawings are 120 merely examples of suitable actuating means; obviously any other means for actuating the tube would serve in effecting our invention, so long as the same co-operates in the functions recited in the claims.

What we claim is:—

1. A pump comprising a tube provided with a suitable valve, actuating means for reciprocating the tube comprising a power cylinder and an elongated piston operating 130

4
therein, said cylinder provided with exhaust ports adapted to be opened near the end of the power stroke but maintained closed by the piston during the balance of its reciprocating movements, said cylinder having a jacketed head for live steam at its steam inlet end.

5 2. A pump comprising a tube provided with a suitable valve, actuating means for reciprocating the tube comprising a power cylinder and an elongated piston operating therein, said cylinder provided with exhaust ports adapted to be opened near the end of the power stroke but maintained closed by the piston during the balance of its reciprocating movements, said cylinder having a jacketed head for live steam at its steam inlet end, and an auxiliary cylinder and a piston operating therein in operative relation with the power piston for cushioning the stroke at the end thereof.

10 15 20 3. A pump comprising a reciprocating tube provided with a suitable valve, actuating means for causing the power stroke in

said reciprocating movement of the tube and an auxiliary cylinder and piston operating therein, in operative relationship with the actuating means and moving with the reciprocating tube for cushioning the return stroke of the reciprocating tube at the end thereof.

4. A pump comprising a tube provided with a suitable valve, actuating means for reciprocating the tube comprising a power cylinder and an elongated piston operating therein, said cylinder provided with exhaust ports adapted to be opened near the end of the power stroke but maintained closed by the piston during the balance of its reciprocating movements, said cylinder having a 40 jacketed head for live steam at its steam inlet end, and means forming an air cushion adapted to be compressed at the end of the power stroke and to react in connection with the return stroke.

EDWARD N. TRUMP.
FRANK FRIEDRICH.
